J. RITTER, JR

TRUNK DRAWER ATTACHMENT

Filed May 14, 1923

FIG. 1.

FIG. 2.

FIG. 3.

INVENTOR.

BY *Julius Ritter Jr.*
Morsell, Keeney & Morsell
ATTORNEY.

UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

TRUNK-DRAWER ATTACHMENT.

Application filed May 14, 1923. Serial No. 688,853.

This invention relates to improvements in trunk drawer attachments.

It is the present practice in trunk manufacture to provide drawers in the wardrobe section which either slide or are hinged to swing outwardly to gain access thereto. Slidable drawers cannot be pulled entirely out without liability of accidentally dropping and hinged drawers require chains or other flexible means for holding them in their outer position. Chains or other like means stretch or break and extend outside of the trunk when the drawer is in its outer position and are otherwise objectionable. Furthermore, the chain or cord support interfered with the metal binding of the front edge portions of the drawer.

It is one of the objects of the present invention to overcome the before mentioned objectionable features and provide a trunk drawer attachment in which the drawer may be swung outwardly to open position while the attachment is entirely out of sight within the trunk section.

A further object of the invention is to provide a trunk drawer attachment which while firmly attaching the drawer to the trunk section so it can be easily swung outwardly and supported in its outer position, also permits the drawer to be easily and freely removed when desired.

A further object of the invention is to provide a trunk drawer attachment which is of simple construction, is strong and durable and is well adapted for the purpose described.

With the above and other objects in view, the invention consists of the improved trunk drawer attachment and its parts and combinations as set forth in the claims, and all equivalents thereof.

In the accompanying drawing in which the same reference characters indicate the same parts in all of the views:

Fig. 1 is a horizontal sectional view of the wardrobe section of a trunk provided with the improved attachment;

Fig. 2 is an enlarged sectional detail view of one of the corner portions of the attachment; and

Fig. 3 is a vertical sectional view thereof taken on line 3—3 of Fig. 1.

Referring to the drawing, the numeral 5 indicates the wardrobe section of a trunk which is adapted in use to rest in an up-

right position and is formed with an open front of ordinary construction. The said section is provided with a skeleton shelf or drawer support 6 which is formed of angled side members 7 mounted on the opposite side walls of the trunk section and cross strip brace members 8 riveted to the side members. Said brace members also serve to reinforce the opposite sides of the trunk section. The front edge portions of the opposite sides of the said section have mounted thereon angled side members 9 with the stop flange portions 10 extending towards each other. The lower end portions of the flange portions 10 are curved inwardly and upwardly to form bearing hooks 11 for the trunnions 12 projecting laterally from the lower, front opposite corners of the drawer 13. The upper end portions of said flanges 10 are bent inwardly to form stop portions 14.

Angled members 15 mounted on the opposite sides of the drawer 13 are positioned to bear against the flanges 10 of the trunk section when the drawer is in its outer position as shown in the drawing. As thus shown, the angled members 15 engaging the flange portions 10 firmly hold the drawer in its outer position while the stop portions 14 prevent the drawer from being accidentally moved upwardly and disengaged from the support.

While the shelf 6 will firmly support the drawer in closed position, additional means is provided in the form of stop members 16 mounted on the front portion of the drawer 13 which engage the front edge portions of the trunk section when the drawer is in its inner position.

The drawer is provided with a hinged cover 16' which is held in closed position by snap straps 17 and when the drawer is in its inner position within the trunk section the cover is vertically disposed.

If it is desired to remove the drawer from the trunk section, it is only necessary to swing the drawer partly outwardly and then raise it bodily upwardly to clear the trunnions 12 and the angled members 15 from the flanges 10 and the hooks 11 projecting from said flanges, and it may then be removed from the trunk section.

From the foregoing description, it will be seen that the trunk drawer attachment is of very simple construction and will firmly hold the drawer in either its outer or in-

2
ner position and provides for the removal of the drawer from the trunk section when desired.

What I claim as my invention is:

- 5 1. A trunk drawer attachment, comprising an open sided trunk section having a drawer support, a drawer vertically positioned on said support and having stop members mounted on its front portion for limiting the inward movement of said drawer, and being movable to a horizontal position outside of said trunk, and a bearing and a stop means for maintaining the drawer in said horizontal position, said drawer and 10 stop means permitting the drawer to be easily removed from engagement with the trunk section by an upward movement of the drawer to disengage the bearing and the stop means.
- 15 2. A trunk drawer attachment, comprising an open sided trunk section having a transversely extending drawer support, angled side members mounted on the opposite side portions of the trunk section and

having flange portions extending towards each other, the lower parts of said flanges extending inwardly and upwardly and forming hook like bearings, and the upper portions extending inwardly and forming stop projections, a drawer removably positioned within the trunk section and having trunnions which slidably enter the hook like bearings, and stop members mounted on the opposite sides of the drawer and which engage the side members and the stop projections when the drawer is swung to its outer position to support said drawer in said position and to maintain the trunnions in engagement with the hook like bearings, said drawer when in its outer position being removable from the trunk section by an upward and an inner movement of the drawer to disengage the bearing and the stop means.

In testimony whereof, I affix my signature.

JULIUS RITTER, JR.
